EGG BEATER

Filed May 27, 1930

INVENTOR

Katie Annie Grounds

UNITED STATES PATENT OFFICE

KATIE ANNIE GROMMET, OF OKLAHOMA CITY, OKLAHOMA

EGG BEATER

Application filed May 27, 1930. Serial No. 456,082.

This invention relates to an egg-beater, so called but more generally to an agitator for beating eggs, frosting and the like, and it is an object of the invention to provide means for permitting the same to be attached to a table or ledge for use, without the use of the hands for holding the same, if desired.

On the drawing, accompanying and forming a part of the specification,

10 Figure 1 is an elevation of the invention, and applied to a kitchen fixture, for use, and

Figure 2 is a fragmentary view of the clamping device made from a single piece of sheet metal.

15 On the sheet of drawings, like characters of reference will indicate like parts.

In the case of Figure 1, a clamp, consisting of an upper jaw 3 and a lower jaw 4, extends laterally and outwardly from a bar

20 5, to which bar a handle 6 is applied, and between these jaws 3 and 4, the ledge 7 of a table or other kitchen fixture 8 is inserted, as seen.

25 Through the under jaw 4 is passed a screw-threaded stud 9 to which is swiveled at the upper end a plate 10 to take to the under side of the ledge 7, and the end of stud 9 is provided with a winged finger piece 11.

Secured to the bar 5 and depending therefrom is the usual shank 12 to which the ratchet wheel 13 is shafted at 14, and the lower end of the shank 12 is bent to form a bearing 15 and a bearing 16 to receive the shafts of the gear wheels 17 and 18 that not only mesh with the wheel 13, but to which also are secured the agitators or dashers 19, 20, 21 and 22, journaled upon the usual bearing 23, the wheel 13 being provided with a handle 24 for rotating the wheel 13 and the dashers 19, 20, 21 and 22.

So far the clamp idea has been described with reference to a casting, and now, for the purpose of making the entire clamp from sheet metal in one continuous formation, Figure 2 will be described.

Commencing at 25 a handle 26 is formed and from that handle and depending downward a shank 27 terminates in an out bend to a lateral lip 28 bent back again upon itself for double strengthening, and then bent

again into a downward shank 29 which again is bent outward laterally in the same direction as lip 28 to form another lip 30 again bent upon itself for double strengthening, and then downward to a shank 31, (shown 55 broken off) and which would terminate, of course in the parts shown in Figure 1.

Inset between the upper lateral lip 28 and the lower lateral lip 30 is a brace consisting of an upper and lower bar 32 and 33, and an upright brace 34, and parts are suitably riveted together as indicated. This makes a substantial formation for practical use.

Through the lower formation of the clamp-parts 30 and 33, the stud 35 is screw-threaded, and carries the swivel plate 36 and the winged finger piece 37.

Thus it will be seen that there is provided for the usual egg beater, or other like agitator, a method and means for affixing the same into place for use upon a fixed place without the need of using the handles 6, 26, at will.

Having thus set forth the invention, I claim:

An egg beater having the usual agitators and devices for operating them, and a sheet metal strip supporting and rising from same and being turned twice upon itself to form a reinforced lateral under lip for a clamp, 80 and upwardly extending bar, a twice bent formation forming a reinforced laterally extended over lip of greater length than the under lip, a handle terminating the sheet metal strip, a second strip formed into a U-shaped brace between the upper and lower lips the bight of the U engaging said upwardly extending bar and a thumb screw passing through the lower lip and one of the parts of the brace. 85 90

In witness whereof I have hereunto set my hand this 16th day of May, in the year of our Lord nineteen hundred and thirty.

KATIE ANNIE GROMMET.
